[57] CLAIM

The ornamental design for a package for a toothbrush, as shown.

DESCRIPTION

FIG. 1 is a top, front and right side perspective view of a package for a toothbrush showing the new design;

FIG. 2 is a right side view thereof;

FIG. 3 is a left side view thereof;

FIG. 4 is a top side view thereof;

FIG. 5 is a bottom side view thereof;

FIG. 6 is a rear side view thereof; and,

FIG. 7 is a front side view thereof.

The broken line showing an outline of a toothbrush is for illustrative purpose only and forms no part of the claim.
